US0D1102413S

(12) **United States Design Patent** (10) **Patent No.:** **US D1,102,413 S**
(45) **Date of Patent:** **** Nov. 18, 2025**

(54) **CASE FOR A MOBILE DEVICE**

(71) Applicant: **GOOGLE LLC**, Mountain View, CA (US)

(72) Inventors: **Arthur Kenzo Debaigue**, San Francisco, CA (US); **Jessica Sheung-yan NG**, Mill Valley, CA (US); **Mark Zaveson**, Antioch, IL (US)

(73) Assignee: **Google LLC**, Mountain View, CA (US)

(**) Term: **15 Years**

(21) Appl. No.: **29/919,318**

(22) Filed: **Dec. 4, 2023**

Related U.S. Application Data

(62) Division of application No. 29/815,144, filed on Nov. 11, 2021, now Pat. No. Des. 1,020,715.

(51) **LOC (15) Cl.** **03-01**

(52) **U.S. Cl.**

USPC **D14/250**

(58) **Field of Classification Search**

USPC ..... D3/201, 218, 226, 247, 249, 269, 303; D13/107, 108, 113, 118, 119; D14/138 G, 217, 248, 250–253, 432, 440 CPC H04B 1/3888; H04B 2001/3894; H04B 1/3827; H04M 1/0283; H04M 1/0202; A45F 2005/028; A45F 2200/0525; A45C 11/002; A45C 11/321; A45C 11/182; A45C 13/008; A45C 11/22; A45C 13/103

(57) **CLAIM**

The ornamental design for a case for a mobile device, as shown and described.

DESCRIPTION

FIG. 1 is a top, front, right side perspective view of a case for a mobile device showing our new design;

FIG. 2 is a top, back, left side perspective view thereof;

FIG. 3 is a front view thereof;

FIG. 4 is a back view thereof;

FIG. 5 is a right side view thereof;

FIG. 6 is a left side view thereof;

FIG. 7 is a top view thereof; and,

FIG. 8 is a bottom view thereof.

The dot-dash lines define the bounds of the claimed design of this embodiment and form no part thereof.

1 Claim, 4 Drawing Sheets
